UNITED STATES PATENT OFFICE.

ESKIL WERNER SOHLMAN, OF CHARLESTON, WASHINGTON.

CLUTCH.

Application filed March 13, 1922. Serial No. 543,358.

To all whom it may concern:

Be it known that I, ESKIL W. SOHLMAN, a citizen of the United States, residing at Charleston, in the county of Kitsap and 5 State of Washington, have invented certain new and useful Improvements in Clutches, of which the following is a specification.

This invention relates to clutches, and more particularly to centrifugally controlled 10 clutches for rotatable machinery.

An object of the invention is the provision of a friction clutch by means of which a rotating part may be driven at a substantially constant rate of speed. The clutch 15 elements are slidably mounted on the rotating part and are attached to weights which are thrown outwardly by centrifugal force. Suitable means are provided for counteracting the outward movement of the 20 clutch elements whereby the engagement of the clutch elements with the drive shaft is varied in proportion to the speed of the machine.

In the present application, I have illustrated 25 the invention applied to a toy phonograph, but it is apparent that it may be employed in other places where a substantially constant speed is desired.

In the accompanying drawings, I have 30 shown one embodiment of the invention. In this showing:

Figure 1 is a front elevation of a phonograph showing the invention applied,

Figure 2 is a plan view,

Figure 3 is a vertical sectional view on 35 line 3—3 of Figure 1,

Figure 4 is a bottom plan view of the turntable,

Figure 5 is a detail sectional view on line 40 5—5 of Figure 1,

Figure 6 is a perspective view of the governor, and,

Figure 7 is a detail sectional view on line 45 7—7 of Figure 1.

Referring to the drawings, the reference 50 numeral 1 designates a base having a pair of standards 2 and 3 secured to the upper surface. The standard 3 is extended horizontally, as at 4, and secured to the standard 2 forming a horizontal surface or support. The front face of the standard 3 is provided with a recess 5. A shaft 6 is mounted in the standard 3 and projects above the upper face of the horizontal portion 4. A friction roller 7 is mounted on this shaft in the recess 5. This roller is adapted

to engage a friction wheel 8, mounted on a shaft 9, supported in suitable bearings in the supports 2 and 3. The shaft is provided with a crank or handle 10.

A turntable 11 is mounted on the shaft 6, and this turntable is adapted to receive the usual record 12. The under side of the turntable is provided with suitable governing mechanism to maintain a constant rate of 65 revolution. As shown, a plurality of guides 13 are secured to the turntable and the governor mechanism consists of a plurality of radial arms 14, slidably mounted in the guides. The inner ends of these arms are 70 secured to friction clutch members 15. The inner faces of the clutch members are provided with semi-circular recesses 16, adapted to receive the shaft 6. These clutch members are surrounded by an elastic member 17, 75 which tends to hold them in engagement with the shaft 6. The outer ends of the arms 13 are provided with weights 18.

The combined amplifier and sound box 80 comprises a cylindrical metallic member 19, which is secured to an arm 20, formed by card board or other relatively stiff material. As shown, this arm comprises a pair of substantially parallel portions which pass around and are loosely supported by a pin 85 21 arranged on the top of the standard 2. Suitable fastening members 22 pass through the ends of the arm and the adjacent sides of the member 19. A needle holder 24 is mounted in the periphery of the sound box 90 and secured therein by suitable fastening means 25. This needle holder is provided with a recess for the reception of a needle 26 which is retained in position by means of a set screw 27.

To operate the phonograph, the shaft 9 is turned by hand by means of crank 10. The governor maintains the turntable at a constant speed at all times. The weights 18 are moved outwardly by centrifugal force 100 and tend to draw the clutch members away from the shaft. The clutch members, however, are maintained in partial engagement with the shaft by the elastic member 17 which exerts a constant and uniform pressure on the shaft to maintain a uniform speed.

The construction of the sound box 19 eliminates the necessity of an amplifier or horn, and furnishes a clear resonant tone.

It is to be understood that the form of my invention herewith shown and described

is to be taken as a preferred example of the same, and that various changes in the shape, size, and arrangement of parts may be resorted to without departing from the spirit of the invention or the scope of the subjoined claims.

I claim:

1. In a centrifugal clutch, a shaft, a driven member, a plurality of U-shaped supporting devices secured to said member, arms slidably mounted therein, weights secured to the outer ends of said arms, clutch elements carried by the inner ends of said arms, and means for exerting a constant inward pressure on said clutch elements to normally maintain them in engagement with said shaft.
2. In a centrifugal clutch, a shaft, a driven member, and means for connecting said member to said shaft, said means comprising guides secured to said member, arms slidably mounted in said guides, weights secured to the outer ends of said arms, the inner ends of said arms being offset, clutch elements

mounted on the offset portions of said arms, 25 and means for exerting a constant inward pressure on said clutch elements to maintain them in engagement with said shaft.

3. In a centrifugal clutch, a shaft, a driven member, and means for connecting said member to said shaft, said means comprising a plurality of U-shaped supporting devices secured to said member, arms slidably mounted in said supporting devices, weights carried by the outer ends of said arms, substantially rectangular clutch elements secured to the inner ends of said arms, said clutch elements being provided with recesses 35 for the reception of said shaft, and an elastic member surrounding said clutch elements 40 to exert a constant inward pressure thereon.

In testimony whereof I affix my signature in presence of two witnesses.

ESKIL WERNER SOHLMAN.

Witnesses:

HARRY COURTRIGHT,
F. W. ROANE.
